(57) **CLAIM**

The ornamental design for a circumcision device, as shown and described.

DESCRIPTION

FIG. 1 is an upper perspective view of a circumcision device showing our new design in an open condition;

FIG. 2 is a top view thereof in the open condition;

FIG. 3 is a front elevation view thereof in the open condition;

FIG. 4 is a left side elevation view thereof in the open condition;

FIG. 5 is a lower perspective view thereof in the open condition;

FIG. 6 is a bottom view thereof in the open condition;

FIG. 7 is a rear elevation view thereof in the open condition;

FIG. 8 is a right side elevation view thereof in the open condition;

FIG. 9 is an upper perspective view thereof in a closed condition prior to use;

FIG. 10 is a top view thereof in the closed condition prior to use;

FIG. 11 is a front elevation view thereof in the closed condition prior to use;

FIG. 12 is a bottom view thereof in the closed condition prior to use;

FIG. 13 is a rear elevation view thereof in the closed condition prior to use;

FIG. 14 is a left side elevation view thereof in the closed condition prior to use;

FIG. 15 is a right side elevation view thereof in the closed condition prior to use;

FIG. 16 is an upper perspective view thereof in the closed condition after use;

FIG. 17 is a top view thereof in the closed condition after use;

FIG. 18 is a front elevation view thereof in the closed condition after use;

FIG. 19 is a bottom view thereof in the closed condition after use;

(Continued)

FIG. 20 is a rear elevation view thereof in the closed condition after use;

FIG. 21 is a left side elevation view thereof in the closed condition after use; and,

FIG. 22 is a right side elevation view thereof in the closed condition after use.

The broken lines in the drawings illustrate portions of the circumcision device that form no part of the claimed design.
